UNITED STATES PATENT OFFICE

94,767

DESIGN FOR A JUMPING HORSE

Robert J. Joutras, Joliet, Ill., assignor to Jumbo,
Inc., a corporation of Illinois

Application December 13, 1934, Serial No. 54,406

Term of patent 7 years

To all whom it may concern:

Be it known that I, Robert J. Joutras, a citizen of the United States, residing at Joliet, Illinois, have invented a new, original, and ornamental Design for a Jumping Horse, of which the following is a specification, reference being had to the accompanying drawing in which:

Fig. 1 is a side elevation of a jumping horse, showing my new design;

Fig. 2 is a top plan view; and
Fig. 3 is a front elevation.

I claim:

The ornamental design for a jumping horse, as shown.

ROBERT J. JOUTRAS.
